ARTIFICIAL HAND AND MEANS FOR
ACTUATING THE SAME

Frank V. Eberle, Newark, N. J.

Application December 14, 1942, Serial No. 468,950

6 Claims.

(Cl. 3—12)

This invention relates to artificial limbs and more particularly to an improved artificial hand and means for actuating the same. This application is a continuation-in-part of my co-pending patent application, Serial No. 443,889, filed May 21, 1942.

One of the objects of the invention is to provide an improved artificial hand of simple and economical construction by means of which complete closing and opening of the fist can be accomplished with a minimum of effort.

Another object is to provide a novel and improved means controlled by the movement of the remaining limb stump for actuating the artificial hand.

Other objects and advantages inherent in the invention will become apparent from the following specification taken in conjunction with the accompanying drawings which disclose by way of example an embodiment of the invention together with possible modifications.

Artificial appliances have heretofore been used to replace the missing member. However, because of the unsatisfactory experiences with the ordinary mechanical limb, attention has been directed toward the development of a substitute limb in which the control can be achieved by the movements of the remaining limb stump. In order to accomplish the intended purpose, it is imperative that the artificial limb be highly sensitive and immediately responsive to even minor impulses produced by the limb stump.

It is, therefore, the particular purpose of the present invention to provide an artificial limb in which prosthesis can be activated by impulses provided by the limb stump.

In the drawings:

Figure 1 is a cross-sectional view of an artificial hand according to the invention with the adjacent portions of the wrist and the actuating lever mechanism;

Figure 2 is a top plan view with the top plate removed;

Figure 3 is a detailed view of the locking mechanism;

Figure 4 is a plan view of the mechanism transmitting impulses of the arm stump to the lever mechanism of the artificial hand;

Figure 5 is a side view of Fig. 4 with a portion broken away;

Figure 6 is a side view of a modification together with a portion of the stump in which the prosthesis is activated by the mechanical movement of the stump;

Figure 7 is a side view of another modification

together with a portion of the stump for mechanical activation of the prosthesis;

Referring in detail to the drawings, a frame or casing 10 represents the palm and the back of the hand. The front portion of casing 10 is provided with an opening 11 in which the knuckle portions of fingers 12 are pivoted on a shaft 13.

The thumb 14 is similarly pivoted to a shaft 16 and extending through an opening 15 of casing 10.

An arched actuating lever 17 extends from the knuckle portion of the fingers 12 into the casing 10. A corresponding arched lever 18 extends from the thumb 14 in opposite relationship to a lever 17. Levers 17 and 18 are so disposed that their ends move in substantially parallel planes toward and away from one another.

A crank 19 is keyed to the shaft 20 which is rotatably mounted in a boss 21, which latter is preferably cast integrally with casing 10.

An arched link 22 connects lever 17 to the crank 19. A second straight link 23 connects the lever 18 to crank 19. The pivot point of the link 23 is spaced from the pivot point of link 22 on crank 19 for the purpose of providing the relative movement between fingers 12 and thumb 14.

Crank 19 is actuated by a linear movement of a rod 24 which is pivoted to a pin 25 which, in turn, is anchored to crank 19.

To shaft 20 is also keyed a toothed segment 26 so as to move jointly with crank 19. A pawl 27 cooperates with toothed segment 26 and is pivoted at 28 to a lever 29 which, in turn, is journaled at 20 to boss 21.

Lever 29 has an arm 31, the end of which is connected to the inside of the casing 10 by means of a heavy spring 32. A light spring 33 connects pawl 27 with a second arm 34 of lever 29. By virtue of this construction, the pawl will become disengaged from the toothed segment 26 immediately upon release of the locking mechanism, which will be hereinafter described, and jump back to its normal position. The arm 34 limits the return movement of the lever 29 by striking the underlying surface of the casing 10; this position is shown in Figure 3.

The locking mechanism comprises a plate 35 which is pivoted at 36 to a boss 37. The plate is rotated by a lever 38 which projects into the palm through the opening 39 in casing 10. A link 40 is pivoted at one end to plate 35 and at the other end to pawl 27 eccentrically of pivot point 28 of pawl 27.

When lever 38 is pushed forward in the direction of the arrow in Figure 3, it first brings the

pawl into engagement with the toothed segment 26 against the strength of spring 33 and without rotation of segment 26. Further movement of the lever 38 will rotate the segment 26 together with the crank 19 and thus bring the fingers 12 and the thumb 14 tight together. The various levers and pivot points are arranged so that spring 32 will lock lever 38 in its forward locking position. By reason of this construction the force of the grip can be increased once contact has been made between the object and the fingers and the thumb and a tight grip of small objects is secured. It will also be understood that the fingers and thumb can be locked in any position intermediate the fully opened and fully closed position.

The casing 10 is provided with a wrist collar 41 which may be rotatable with respect to the casing so as to provide pronation and supination of the hand. To the wrist collar 41 is attached a cuff 59 by any suitable means.

As shown in Figures 4 and 5, the prosthesis is activated by the movement of the limb stump. The limb stump is supported in a cup 66 which is pivoted at 58 to braces 67 fastened to a support 55. This support is secured to the limb stump by any suitable means. Braces 67 are pivoted to brace 60 at 61 to form an elbow joint. Braces 60, in turn, are fastened to the cuff 59. The casing 10 is rotatable mounted in the cuff 59, as illustrated in Figure 1. Rod 24 is connected to one arm of a lever 62 by means of a link 63, but is rotatable in relation to said link. This is attained by providing the end of rod 24 with a flange which is rotatable in a suitable recess provided in the member 63. The other arm of lever 62 is pivoted to a shackle 64 which at the other end is connected to braces 67 by a pivot 68a. Shackle 64 is bent at 65 so as to cause longitudinal movement of the shackle 64 and a pivotal movement of lever 62 when the stump and the cup 66 are moved. The lever 62 is pivotally supported at 62a upon a support 62b connected to the cuff 59.

An artificial limb according to my invention is operated as follows:

If the artificial hand is to be opened or closed, the person using the hand moves cup 66, for example, by bending his limb stump. Any movement of cup 66 causes an upward or downward movement of shackle 64 which, in turn, will rock lever 62. Assuming that the right arm of lever 62 is moved downward, rod 24 will be pushed into the hand. This movement of rod 24 will cause crank 19 to pivot about its axle 20. The pivotal movement of crank 19 is transferred to fingers 12 by links 22 and 17 and to thumb 14 by links 23 and 18. It is obvious from Figs. 4 and 5 the original movements of cup 66 will be transmitted to the artificial hand at an increased ratio so that even slight movements of the limb stump will be sufficient to actuate the hand.

As previously explained, a movement of rod 24 into the hand will result in an opening of the hand. Conversely a retraction of the rod 24 from the hand by an opposite movement of cup 66 will cause a closing of the hand. The locking device permits a locking of the fingers and the thumb in any desired intermediate position. It also secures a tight grip on any small object. If a hard object is to be gripped between the fingers the user of the hand first closes his fingers as tight as he is able to do by a movement of the limb stump or with his good hand. Then lever 38 of the locking device, located in the palm of the hand, is slowly pushed upwards. Light spring 33 will close the fingers partly but not too tight.

8 The final tightening is made by heavy spring 32. In other words, if a hard object is to be gripped, the light spring will yield to a certain extent and permit a closure of the above-described locking device without any strain on any part of the lock, yet the hard object will be securely gripped between the fingers.

10 In the modification shown in Figure 6, the prosthesis is activated by movement of the stump supported in a cup 66. A two-arm lever 67 which is pivoted to a brace 68 is rocked by the movement of cup 66 by means of a leverage mechanism including links 69 and 70 which are pivoted to a cross-bar 71. The brace 68 is connected at 68a to the cup 66. One end of cross-bar 71 is connected to one arm of lever 67 by means of a link 72. The other end of cross-bar 71 is pivoted to a bell crank 73 which, in turn, is pivoted to the other arm of lever 67. A second leverage mechanism includes the following parts. Bell crank 73 is connected by means of a link 74 to one arm of another bell crank 75 which is pivoted at 76 to a brace 77. The other arm of bell crank 75 is pivoted to rod 24. The joint between braces 68 and 77 corresponds to the elbow joint in the arm which is activated by separate means not forming part of the instant invention.

15 As it is apparent from Fig. 6, movements of cup 66 will result in a rocking of lever 67. The 30 rocking motion of lever 67 is transmitted by bell-crank 73, link 74 and bell-crank 75 to rod 24. Due to the arrangement of the various links and bell-cranks, the original impulse produced by a 25 movement of cup 66 will be conveyed to the hand 35 at an increased ratio.

20 A movement of cup 66 in one direction will cause a movement of rod 24 resulting in an opening of the hand as previously explained, and a movement of cup 66 in the opposite direction will 40 result in a retraction of rod 24 from the handle and hence in a closing of the hand.

25 Figure 7 shows another modification wherein the prosthesis is activated by the mechanical movement of the stump. A lever 78 is pivoted to a brace 79. One arm of lever 78 is connected through a link 80 to a bracket 81 which is fixed to a cup 82. The other arm of lever 78 is connected through a link 83 to a bell crank 84. Bell crank 84 is, in turn, pivoted to a bracket 85 which is anchored to brace 79. The other arm of bell crank 84 is connected to actuating rod 24.

30 A movement of cup 82 will be transmitted by link 80 to lever 78 and cause a rocking movement of this lever. The movements of lever 78 will 55 be conveyed by link 83 to the rod 24 and cause an opening or closing of the hand as previously explained. It will be noted that the arrangement of the various levers and links results in a transmission of the cup movements at an increased 60 ratio. The wrist collar 41 shown in Figure 1 may be conveniently employed in connection with the devices shown in Figures 6 and 7.

65 It will be understood that the invention has been described by way of example and not by way of limitation. The invention lends itself to a variety of expressions within the scope of the appended claims.

What is claimed is:

70 1. An artificial limb comprising an artificial hand including a frame, a series of fingers and a thumb pivoted to said frame, a pair of arcuate levers connected to said fingers and thumb to open and close the hand, said levers being disposed in opposing relationship with their free ends movable in substantially parallel arcs, a

crank, a longitudinally movable rod for actuating said crank, a link connecting each of said levers with said crank, said links being so disposed as to transform the linear movement of said rod into the pivotal movement of said fingers and thumb, a toothed rack movable with said rod and connected to said crank, a pawl for engaging said rack, a leverage mechanism connected to said pawl for moving said rack a predetermined distance, a two-armed lever pivoted to said pawl, a light spring between one arm of said lever and said pawl whereby said pawl will be disengaged from said rack immediately upon release of said leverage mechanism, a second heavier spring between said lever and said frame for locking said pawl in a predetermined position of said leverage mechanism and means controlled by the remaining stump for moving said rod.

2. An artificial limb comprising an artificial hand including a frame, a series of fingers and a thumb pivoted to said frame, a pair of arcuate levers connected to said fingers and thumb to open and close the hand, said levers being disposed in opposing relationship with their free ends movable in substantially parallel arcs, a crank, a longitudinally movable rod for actuating said crank, a link connecting each of said levers with said crank, said links being so disposed as to transform the linear movement of said rod into the pivotal movement of said fingers and said thumb, a toothed rack movable with said rod and connected to said crank, a pawl for engaging said rack, a leverage mechanism connected to said pawl for moving said rack a predetermined distance, a two-armed lever pivoted to said pawl, a light spring between said lever and said pawl whereby said pawl will be disengaged from said rack immediately upon release of said leverage mechanism, a second heavier spring between said lever and said frame for locking said pawl in a predetermined position of said leverage mechanism, and means controlled by the remaining stump for moving said rod, said means including a leverage mechanism for actuation by said limb stump and a link mechanism for transmitting the movement of said latter leverage mechanism to said rod.

3. An artificial limb comprising an artificial hand including a frame, a series of fingers and a thumb pivoted to said frame, a pair of arcuate levers connected to said fingers and thumb to open and close the hand, said levers being disposed in opposing relationship with their free ends movable in substantially parallel arcs, a crank, a longitudinally movable rod for actuating said crank, a link connecting each of said levers with said crank, said links being so disposed as to transform the linear movement of said rod into the pivotal movement of said fingers and said thumb, a toothed rack movable with said rod and connected to said crank, a pawl for engaging said rack, a leverage mechanism connected to said pawl for moving said rack a predetermined distance, a two-armed lever pivoted to said pawl, a light spring between said lever and said pawl whereby said pawl will be disengaged from said rack immediately upon release of said leverage mechanism, a second heavier spring between said lever and said frame for locking said pawl in a predetermined position of said leverage mechanism, and means controlled by the remaining stump for moving said

rod, said means including a leverage mechanism for actuation by said limb stump and a link mechanism for transmitting the movement of said latter leverage mechanism to said rod at an increased ratio.

4. An artificial limb comprising an artificial hand including a frame, a series of fingers and a thumb pivoted to said frame, a pair of arcuate levers connected to said fingers and thumb to open and close the hand, said levers being disposed in opposing relationship with their free ends movable in substantially parallel arcs, a crank, a longitudinally movable rod for actuating said crank, a link connecting each of said levers with said crank, said links being so disposed as to transform the linear movement of said rod into the pivotal movement of said fingers and thumb and means controlled by the movements of remaining stump of the natural limb for moving said rod, said means including a cup secured to said limb stump, a leverage mechanism for actuation by movements of said stump, a two-arm lever actuated by said leverage mechanism, a second leverage mechanism actuated by said two-arm lever for transmitting the movement of said two-arm lever to said rod.

5. An artificial limb comprising an artificial hand including a frame, a series of fingers and a thumb pivoted to said frame, a pair of arcuate levers connected to said fingers and thumb to open and close the hand, said levers being disposed in opposing relationship with their free ends movable in substantially parallel arcs, a crank, a longitudinally movable rod for actuating said crank, a link connecting each of said levers with said crank, said links being so disposed as to transform the linear movement of said rod into the pivotal movement of said fingers and thumb and means controlled by the movements of the remaining stump of the natural limb for moving said rod, said means including a cup secured to said limb stump, a pivotally supported two-arm lever, a leverage mechanism connecting said cup to one arm of said two-arm lever for transmitting movements of said cup to said arm and a second leverage mechanism connecting said rod to the second arm of said two-arm lever for transmitting movements of said two-arm lever to said rod.

6. An artificial limb comprising an artificial hand including a frame, a series of fingers and a thumb pivoted to said frame, a pair of arcuate levers connected to said fingers and thumb to open and close the hand, said levers being disposed in opposing relationship with their free ends movable in substantially parallel arcs, a crank, a longitudinally movable rod for actuating said crank, a link connecting each of said levers with said crank, said links being so disposed as to transform the linear movement of said rod with the pivotal movement of said fingers and thumb and means controlled by the movements of the remaining stump of the natural limb for moving said rod, said means including a cup secured to said limb stump, a pivotally supported two-arm lever, a bell-crank pivotally connected to one arm of said two-arm lever, a leverage mechanism connecting said cup with one arm of said bell-crank, a second pivotally supported bell-crank, a link connecting one arm of said first bell-crank to one arm of said second bell-crank and a pivotal connection between the other arm of said second bell-crank and said rod.
